NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA

CONDUCTOR CLAMP

Application filed April 6, 1927. Serial No. 181,333.

My invention relates to conductor clamps and particularly to clamps for mounting high-voltage transmission lines.

One object of my invention is to provide a clamp of the above-indicated character that shall embody means for selectively mounting it in different ways.

Another object of my invention is to provide a conductor clamp that shall facilitate mounting the conductor and be easy to manipulate.

A further object of my invention is to provide a combined angular strain and dead-end clamp that shall be simple and durable in construction, economical to manufacture and effective in its operation.

In high-voltage, transmission line, supporting clamps, it is usual to carry stocks of clamps of different types for various kinds of service, such as those in which a supporting link is disposed in alignment with, or at an angle to, the conductor axis.

It is also, usual to provide clamps in which the conductor must be held by the linemen, while the clamping parts are being mounted.

Both of the above-mentioned features cause unnecessary labor and expense and it is my aim to improve the clamps so as to reduce the number of clamps of different types and to facilitate the mounting thereof.

Accordingly, in practicing my invention, I provide a clamp that may be selectively mounted as a clamp of different types and that shall facilitate its mounting, in addition to embodying features which render it economical, durable and effective in operation.

Figure 1, of the accompanying drawing, is a side elevational view of a transmission line clamp embodying my invention; and

Fig. 2 is an enlarged view taken along the line II-II of Fig. 1.

The device comprises, in general, a channel portion 2 for the reception of a conductor 3, a pair of relatively small lips 4 at opposite sides of the conductor adjacent to one end of the channel 2, a larger lip 5 adjacent to the other end of the channel 2,

mounting portions 7 and 8, for cooperation with a link 9, and a clamping member or members 10.

The portion 2 comprises laterally-projecting portions 6 and a central under reinforcing web 11 that extends between downwardly curved portions adjacent to the lips 4 and 5.

The lip 5 is larger, or longer, than the lips 4 and curves downwardly, or laterally away, from the conductor-receiving portion 2, whereby the conductor may be dead-ended at, or by-passed around, an insulator (not shown) at the outer end of the link 9.

The mounting portions 7 and 8 are in the form of apertured bosses that are formed on a web extension 14 and are diagonally disposed with reference to the clamp and approximately at one end thereof.

Thus, the link 9 may be mounted in alignment with the axis of the main body of the conductor, as shown in full lines, or be mounted at an angle to said axis, as indicated by broken lines.

In the above-described structure, the conductor 3 maintains its position between the parts 2, 4, 5 and 14 while the member or members 10 and bolts 12 are being mounted and without manual holding, as in clamps heretofore employed.

The clamp is exceedingly simple, compact, neat and rugged in structure, economical to manufacture, easy to manipulate and effective in its operation, as well as providing a variety of clamps in one device to reduce the stocks thereof necessary to be carried.

While I have shown and described a particular form of my invention, changes may be effected therein without departing from the spirit and scope thereof, as set forth in the appended claims.

I claim as my invention:

1. A conductor clamp comprising a conductor-receiving portion, means for clamping the conductor to said portion and means adjacent to one end of the clamp having diagonally related portions for receiving a mounting link in different angularly-related 10.

positions, in one of which positions the link is substantially in alignment with the conductor when under tension.

2. A conductor clamp comprising a conductor-receiving portion including a portion adjacent to one end thereof having diagonally located apertured portions for attaching the clamp to a mounting link, said link being thus adapted to have different angularly-related positions, in one of which it is substantially in alignment with the conductor when under tension, and means for clamping the conductor to said receiving portion.

3. A transmission-line-conductor clamp comprising means for clamping a conductor including a member for extension along a span section of the conductor and permitting another portion of the conductor to extend laterally to said span section adjacent to the clamp, and means for receiving a mounting link in different angularly-related positions, in one of which the link is substantially in alignment with said span section of the conductor under tension-load conditions.

4. A transmission-line-conductor clamp comprising means for clamping a conductor including a conductor-receiving channel member for extension along a span section of the conductor and having a laterally-curved portion along which another portion of the conductor extends and a mounting link, said channel member including means for receiving said link in different angularly-related positions, in one of which the link is substantially in alignment with said span section of the conductor under tension-load conditions.

40 In testimony whereof, I have hereunto subscribed my name this 31st day of March, 1927.

NILS A. WAHLBERG.
